**PRISMATIC PHOTOELECTRIC-CONTROLLED
OUT-DOOR LUMINAIRE**

Frank Van Steenhoven, Newark, Ohio, assignor to
Holophane Company, Inc., New York, N.Y., a corpo-
ration of Delaware

Filed July 26, 1963, Ser. No. 75,985

Term of patent 14 years

(Cl. D48—4)

T1q.1.

T1q.2.

FIG. 1 is a perspective view of a prismatic photoelectric-controlled out-door luminaire showing my new design;

FIG. 2 is a side view thereof;

FIG. 3 is a top plan view thereof;

FIG. 4 is a bottom view thereof; and

FIG. 5 is a fragmentary front elevation thereof.

The dominant features of my design reside in the portions shown in full lines, which portions are characterized by the specific configuration of the photoelectric housing unit in association with the lamp member as shown.

I claim:

The ornamental design for a prismatic photoelectric-

controlled out-door luminaire, substantially as shown and described.
